MECHANICALLY ACTUATED PRESS FOR
TRIM TILE

Roland List and Anderson Flynn, Zanesville,
Ohio, assignors to The Mosaic Tile Company,
Zanesville, Ohio, a corporation of Ohio

Application March 30, 1945, Serial No. 585,578

9 Claims. (Cl. 25—94)

1

This invention relates to improvements in mechanically-actuated presses for trim tile.

One of the objects of this invention is to produce a mechanically-actuated press which will be capable of mechanically producing trim tile, such as heretofore has been made only in hand-operated friction-driven presses. Trim tile so made on our mechanically-actuated press will when finished be as firm, strong and uniform in structure as the trim tile made on friction-driven presses and will be useful as edging tile, such as cap tile or base tile in tile panels.

Another object of our invention is to provide in a press of the character specified, special cooperating heads on the upper and lower plungers of a press which are provided with cooperating depending and upwardly projecting portions to press edge-ribs on trim tile within a die cavity, mechanically-actuated means on the press for elevating the lower plunger after pressing a trim tile to raise the lower plunger into a tile-ejectable position above the die cavity, and mechanically-actuated means operable first to push such pressed tile across said plunger and die cavity and thereafter having a secondary movement to transfer the pressed tile out of the press and for introducing or charging clay in suitable quantity and disposition into the die cavity to produce a trim-tile.

Another object of our invention is to provide in combination with a novel tile-ejecting and charging means that will have tile-ejecting movements adapted to initially move a tile across the lower plunger of the press and out of the die cavity, of mechanical means for transferring the tile from a position adjacent to the die cavity to an off-bearing belt, and also to introduce and properly dispose a charge of material suitable for forming or pressing a trim tile.

Still another object of our invention is to provide a combined charging and ejecting mechanism adapted to have a primary tile-pushing movement and a secondary die-charging movement adapted to actuate a tile transfer mechanism whereby a fragile tile, such as a trim tile, will first be slidably pushed a short distance from the die cavity and will thereafter be carried on a transfer mechanism to an off-bearing belt.

Another object of our invention is to provide a transfer mechanism having a reciprocating movement from a position adjacent to the die cavity to a position adjacent to an off-bearing belt and return, and means, preferably comprising a combined ejecting and charging device, for actuating said transfer mechanism to have a tile-transferring movement from said position adjacent to the die cavity to an off-bearing belt, and a resetting movement from the off-bearing belt to a position adjacent to the die cavity.

Another object of this invention is, in a me-

2

chanically-actuated tile press, to provide an ejector and charging mechanism having a novel cycle of movements synchronized at an intermediate position in such cycle of movements with the movement of the ribbed plungers hereinabove specified, whereby an initial quick forward movement thereof will push and move a previously-pressed tile over a part of the floor portion of the lower plunger away from the die cavity and into contact with a transfer mechanism while the lower plunger is raised and the upwardly-projecting rib thereof extends above the level of the die cavity to obstruct a complete forward movement of the ejector and charging mechanism; then will have a dwell or stop in such forward movement timed with a downward lowering movement of the lower plunger to its normal tile-pressing position which lowers said rib and removes the obstruction, thereafter will have continued forward movement rapidly to actuate said transfer mechanism to transfer the pressed tile to an off-bearing belt and also to charge the die-cavity, and finally having a backward, return movement to reset the transfer mechanism and procure another charge of clay.

Still another object of our invention is to provide a tile-transfer mechanism, preferably actuated by a combined ejector and charging device, comprising a grill of spaced bars adapted in an initial position adjacent to the die cavity to receive and support the tile during the initial ejecting movement thereof, and thereafter to move from said initial position to a position adjacent to the off-bearing belt, and in such movement not only to support but to carry the tile from said initial position to final position and then to deliver the tile into contact with the off-bearing belt.

Still another object of our invention is to provide a reciprocating grill mechanism mounted in supporting elements extending along the sides of the die cavity to enable a close approach of said grill mechanism to said cavity to receive and support the tile upon an initial ejection movement thereof from the die cavity, and releasable latching means for said grill mechanism operable by an ejector and charging mechanism for releasably latching said grill mechanism in tile-receiving position and for delivering the tile to an off-bearing belt.

Still another object of our invention is to utilize an ejector and charging device having a pusher portion adapted in its forward movement to extend and pass over an upwardly extending rib of the lower die in the beginning of the ejecting movement.

Still another object of our invention is to provide a cam-actuating mechanism combined with a tile-ejector and charging device that will cause the ejector and charging device to have an inter-

mittent movement or a plurality of separate movements during a forward movement thereof, and these forward movements will be co-related and synchronized with the movements of the plungers to enable initial and quick pushing of a trim tile from the die cavity onto a carrier-grill while the plunger rib is in raised position; then to provide a dwell to enable a lowering of the lower plunger and thereafter to provide a subsequent rapid movement for actuation of a reciprocable grill mechanism to carry the tile from a receiving position in proximity to the die cavity to an off-bearing belt.

With these and other objects in view, the invention comprises the combination of members and arrangement of parts so combined as to contact and cooperate with each other in the performance of the functions and the accomplishment of the results herein contemplated, and comprises in one of its adaptations the species or preferred form illustrated in the accompanying drawings, in which—

Fig. 1 is a view in side elevation of a press embodying the preferred form of our invention;

Fig. 2 is a front elevation;

Fig. 3 is a rear elevation;

Fig. 4 is an illustrative view, partly in section and partly in elevation, having some of the parts shown conventionally and more or less diagrammatic, and showing essential parts of the mechanism of our press in a position at one end of its cycle of operation;

Fig. 5 is an enlarged fragmentary view of the die-cavity and adjacent parts when the press is in the position shown in Fig. 4;

Fig. 6 is a view similar to Fig. 4 showing the essential parts of the press in a position intermediate the ends of the cycle of operation;

Fig. 7 is an enlarged fragmentary sectional view showing the die-cavity, plungers and parts adjacent thereto in the position illustrated in Fig. 6;

Fig. 8 is a view similar to Figs. 4 and 6, showing the essential parts of the press in a position occupied thereby at the opposite ends of the cycle of movement;

Fig. 9 is an enlarged fragmentary section showing the die-cavity and adjacent parts in the position shown in Fig. 8;

Fig. 10 is a view in plan, partly broken away, showing the die-cavity and adjacent devices;

Fig. 14 is a cross-section substantially on the line 14—14 of Fig. 9;

Fig. 15 is a view in plan of the combined charging device and tile ejector or pusher;

Fig. 16 is a section on the line 16—16 of Fig. 15 looking in the direction of the arrows; and

Fig. 17 is a perspective view of a trim-tile such as mechanically pressed by our form of press shown in Figs. 1 to 16.

Referring now to these drawings which illustrate a preferred embodiment of our invention, it will be understood that our mechanical-actuated press for trim tile has certain general features similar to presses employed in the manufacture of flat tile, as for example, the mechanical and hydraulic presses illustrated in expired patents to Yingling #1,268,909 and #1,515,918; and reference is made to these patents for such features and details thereof but in our press the

construction and movements of various parts have been modified, new parts have been employed and new functions have been provided for some of the parts, as hereinafter specified.

Our improved press embodies a main supporting frame including side members 1 provided with suitable bearings for shafts and other parts. A main conventional power-shaft 2 provided with the usual control mechanism, is mounted in bearings in said supporting frame, a mold-casing 3 for the die cavity, a lower plunger or die 4, which in our press has a special head 4a suitable for pressing trim tile and provided with a body or floor portion 4b and upstanding rib 4c, an upper toggle-actuated plunger 5 having a similar cooperating ribbed head 5a provided with a body portion 5b and a downwardly projecting rib 5c, a pitman 6 connecting the die toggle with a crank on the power shaft 2, and a clay reservoir or hopper 7. A reciprocating tile-ejecting and mold-charging device or shaker box is adapted to be operated to move forwardly and rearwardly by cam mechanism actuated by the shaft 2 to convey a charge from the hopper 7 to the die cavity of the mold casing 3. This tile-ejecting and mold-charging device and its operating cam, in accordance with our invention, has a novel forward movement adapted to cooperate with a modified movement of the lower die and with a novel transfer mechanism hereinafter more particularly specified which is arranged closely adjacent to the die cavity and said forward movement of the charging device is divided (1) into an initial relatively rapid movement for partial ejection or movement of a previously pressed tile causing a forward pushing of the tile over or along the surface of the lower plunger head and over or along the top surface of an anti-friction transfer mechanism, and this initial movement is timed to occur while the head of the lower-plunger is moved and positioned above the level of the die cavity and in a position which would obstruct a continuance of such movement; (2) a dwell or stop in said forward movement synchronized to permit downward movement of said lower plunger head into normal tile-pressing position to free the path of said ejector and charger device; (3) a subsequent secondary relatively rapid forward movement of said ejecting mechanism adapted to charge the die and to actuate said transfer mechanism to move the pressed tile to and into contact with an off-bearing belt, and (4) a continuous return movement to loading position.

A support 8 for the lower die 4 is carried by a conventional pair of complementary and vertically slideable side-bars 9 fitted in suitable guides on the frame members 1, and a shaft 10 comprising a pivotal support for the upper member of a toggle 11 is mounted in bearings in the bars 9. The bearing portions 10' of the shaft 10 are positioned eccentrically to the intermediate body section and to one end of the shaft 10 is suitably secured a crank 12 which is connected by a rod 12' with one arm of a bell crank 14 mounted on the frame of the machine and having its other arm provided with a roller 15 with which a cam 16 on the power shaft 2 cooperates, whereby the eccentric toggle-supporting shaft 10 will be rocked in its bearings during each rotation of the shaft 2.

The connecting rod 12' preferably is of conventional construction to enable the length thereof to be varied as desired to vary the angular relationship between the crank 12 and the bell crank 14 and thereby to control the amount of

second pressure adjustment of the toggle 11 produced upon a rocking of the shaft 10.

In accordance with our invention, the pitman 6 is provided on its lower face with a special cam plate or shoe 6' that is adapted to cooperate with a roller 6^a mounted in the main frame 1 to effect, after a pressing operation, an initial upward movement of the lower die head to cause the body or floor portion 4^b to move to a position above the surface of the casing of the die cavity and flush with the upper surface of an anti-friction transfer mechanism or grill hereinafter specified. Such positioning of the lower die head is, of course, necessary to permit the pressed tile to be moved off the die head and out of the die cavity, but the raised position of the die as well as the tile-forming rib thereof forms an obstruction to the conventional movement across the die cavity of the charging and ejecting device. A problem was thus presented as to the ejection from the die and the subsequent further movement out of the press of this trim form of tile. We solved this problem by dividing up the forward ejecting movement of the charging and ejecting device and provided a dwell intermediate the ends thereof, as hereinabove specified, so as to produce an initial movement synchronized with the movement of the lower die into raised position and at this point we effect a partial ejection only of the tile; then we provide a stop or dwell of said device while the lower die is returning to a position below the die cavity so that the obstruction is removed, and then we provide a secondary forward movement, synchronized with the movement of the lower die into lowered position, by which we operate means to complete the ejecting movement of the tile.

The capacity of the mold or the quantity of material it can receive is conventionally regulated by the stop 20 and hand wheels 20^a cooperating with screws 20^b.

Clay is supplied to the hopper or receptacle 7 and a quantity thereof sufficient to form a trim tile or number of trim tiles to be produced at each complete operation of the press is periodically transferred from the hopper to the mold casing by a combined ejecting and charging device 21.

It will be understood that with a given adjustment of the parts of the toggle mechanism, the ultimate travel of the plunger heads toward each other will press a tile of uniform structure, and that the density of the tile may be regulated by the amount of clay introduced into the die cavity.

In accordance with our invention, the combined ejecting and charging device 21 which has the aforesaid divided forward and continuous rearward movements is operated from a novel cam member 27 mounted on the power shaft and moves beneath the dust-box hopper 7 to receive its load and thence forwardly in the aforesaid divided movement to partially eject the previously-pressed tile and thereafter to operate a transfer mechanism to complete transfer of said previously-pressed tile and to deliver its said load to the die-cavity. Said combined ejecting and charging device comprises a carrier or driving section 21 movable forwardly and rearwardly over the table and frame of the die-cavity, and having a rearwardly-extending cut-off plate 21^b which is long enough to close the outlet opening to prevent the escape of material from the hopper 7 during the ejecting and charging movements.

In connection with the ejecting and charging device, a dust agitating device is employed, which comprises a rectangular agitating or shaker-box-section 21^a driven or moved by said carrier sec-

tion, and a frame located in the opening in the front of the charger. The agitator is carried by and moved longitudinally of the charger as the latter moves rearwardly and forwardly. At the rear of the agitator frame a pair of rods 21^c are pivotally connected to rods 21^d and these rods pass beneath the charger and are connected with conventional agitating means arranged at the rear end of the combined ejector and charger.

At its forward end a pivotally connected frame 21^e is provided with U-shaped pushers 21^f projected from the charger and provided at their forward ends with fenders or push bars 21^g of rubber or other soft material to contact with the pressed tile after it is moved above the die cavity, and to move the completed tile to the transfer device hereinafter more particularly described for further handling.

The combined ejecting and charging device 21 is moved from the power shaft 2 by means of the cam member 27 and provided at each side with a rearwardly extending rod or link 22, the rear ends of which rods are connected by a cross bar 23 and are adapted to be engaged by a pair of arms 24 mounted to rock about a given axis in the frame of the machine and one of which has at one end an upwardly extending arm 25 which, at its outer end, is provided with a roller 26 cooperating with the said cam 27 on the main power shaft 2.

In accordance with our invention, the cam member 27 embodies a forward drive-portion 27' embodying an initial forwardly-driving portion 27^a which is adapted to cause the pusher member of the ejecting and charging device to have rapid or quick forward movement over the lower plunger head and to engage and push a pressed tile over said head and out of the die cavity; a dwell or momentary stop portion 27^b adapted to hold the combined ejecting and charging device substantially stationary while the lower plunger is above the die cavity; and a final forward-drive portion 27^c adapted to cause the ejecting and charging device to have a secondary rapid or quick forward movement to operate the transfer mechanism and to charge the mold or die cavity, and this portion 27^c is connected and communicates with a rearward-drive portion 27^d adapted to cause movement of the ejecting and charging device rearwardly and a resetting of the transfer mechanism.

By the action of this cam member, as the shaft is revolved, the combined ejecting and charging device will have the divided or intermittent forward movement and continuous rearward movement hereinabove specified.

It will be apparent, therefore, that the ejecting and charging device 21 will, in its forward movement, first engage and push a pressed tile a short distance over the edge of the die cavity and on to a transfer mechanism, will then pause or dwell momentarily and stop the pushing movement of the pressed tile to permit the lower die to be moved downwardly out of the path of said ejecting and charging device, whereupon said ejecting and charging device will then again move forward to further push and follow up the said pressed tile and also to operate the transfer mechanism hereinafter described so as to carry the pressed tile from the edge of the die-cavity to a conventional off-bearing belt B.

In accordance with our invention, the transfer mechanism comprises a grill 28 on to which the previously-pressed tile is pushed by the pusher member or frame. This grill comprises bars 28' mounted at opposite ends in slides 30 freely mov-

able forwardly and backwardly in grooves 29' formed in the inner side walls and extending the entire length of the guides 29, seated in a depression formed in the bed of the press so as to be flush with the die plates. The grill is moved forwardly and rearwardly by side rails 31 having at their inner ends pivotal connections at 31' with the forward end of the charging and ejecting device 21 and free forwardly-projecting portions having an operative connection with the grill to enable the forward movement thereof with its load of tile. As illustrated, the side rails 31 are provided with slots 31a into which pins 28a on the grill 28 extend and also carry spring-pressed latches 32 adapted to engage with the pins 28a of the grill 28 during the aforesaid secondary forward movement to move the grill and its load forwardly over and along the bed or die frame of the press to a position adjacent to an off-bearing belt 33 at which point pins 34 on latches 32 carried by the side rails 31 are engaged by bevelled portions 35 of the latch-releasing blocks 35 causing the latches 32 to be raised and disengaged or released from the grill pins 28a. Due to inertia, the grill continues its forward movement in the slots 31a until the pins 28a are stopped by pins 34a on the blocks 35 whereupon the tile is delivered to the off-bearing belt.

Further movement of cam 27 causes the ejecting and charging device 21 to move rearwardly or backwardly to the position shown in Figs. 8 and 9. During this movement small lugs 36 at the outer end of the side rails 31 engage outer members of the grill 28 and in the further rearward movement of the rails move or return said grill to the loading position shown in Figs. 4 and 5. During such rearward or return movement, the latches 32 which are provided with inclined-noses 32' ride over the pins 28a on the grill, whereupon said latches 32 assume the position shown in Fig. 5, ready to engage and pull forward the grill on the next ejecting operation.

We will now describe the cycle of movement of the press in so far as the same relates to movements of the tile-ejecting and transferring mechanism and cooperating parts.

Referring now to Figs. 4 and 5 which show the position of the press in which the tile has been formed, and the top plunger 5 is moving upward and the lower plunger 4 is raised to the ejecting position due to the action of the cam plate 6' engaging roller 6a, the cam member 27 has assumed a position in which the ejecting and charging device 21 carrying a pusher 21a has moved back to its loading position. As in the operation of conventional tile presses, the cavity in the shaker box 21a of the ejecting and charging device 21 receives in this position a charge of clay from the hopper 7. At this position in the cycle, the grill 28, mounted as aforesaid on slides 30 which are free to move forwardly and backwardly in the guides 29, has not moved from the position said grill assumes during an actual tile-pressing operation. Now, upon movement of the rails forwardly, the latches 32 engage a pin 28a on the grill, and the forward motion of the side rails 31 which carry the spring-pressed latches 32 will thereupon move the grill 28 and the finished tile forward with any further forward motion of the ejecting and charging device 21 and its shaker box 21a.

Rotation of cam member 27 will force the roller 26 outwardly from its position in relation to shaft 2 shown in Figs. 4 and 5, thus producing a very rapid forward motion of the ejecting and charging device 21 and then owing to the conforma-

tion of the cam at 27b providing the aforesaid momentary dwell, and finally causing it, with the attached forwardly-projecting side rails 31 and the grill 28 to assume the position shown in Figs. 6 and 7 in which the parts are ready for their secondary outward or forward movement along the channel 27c. Just prior to this stage, the movement of the shaft 2 has caused pitman 6 and the attached cam plate 6' to move the lower die to its uppermost position and the pusher 21a during its said initial forward movement has pushed the tile off the said lower die onto the grill 28 and has then stopped or dwelled momentarily. Rotation of said shaft 2 also causes said pitman 6 and cam plate 6' to disengage roller 6a, and this action allows the support 8 for the lower die 4 to move downward to the charging position. The ejecting and charging device will now move forwardly till the cavity of the shaker box 21a is positioned over the die cavity to deliver a charge of clay for the next pressing operation. During the outer or secondary portion of the forward movement of the side rails 31, the pins 34 on the latches 32 strike the bevelled latch-releasing blocks 35 causing latches 32 to be raised and thus disengaged from the pins 28a of the grill 28. Due to inertia, the grill continues its forward motion until the pins 28a are stopped by the pins 34a on the latch-releasing blocks 35 in the position shown in Figs. 8 and 9, whereupon, in this position, the tile carried by the grill is delivered to the off-bearing belt B.

Further movement of the cam member 27 causes the roller 26 to move along the channel 27' (see Figs. 8 and 9) whereupon the ejecting and charging device 21 will be returned to the position shown in Figs. 4 and 5. During this return movement, the lugs 36 engage the front portion of the grill 28, returning it to the position more particularly shown in Figs. 4, 5 and 10 in which position the slides 30 reach the inner ends of the grooves 29' in the guides 29 in which said slides reciprocate, which terminal of the groove 29' functions as a stop to position the grill at its limit of return or rearward movement. During this return or rearward movement, the bevelled edges of the latches 32 engage and ride over the pins 28 on the grill which thus assumes the position shown in Figs. 4 and 5, ready to engage and push forward the grill 28 on the next ejecting operation.

The operation of the tile-pressing portion of the cycle is conventional and exactly similar to that of conventional presses such as shown, for example, in the Yingling Patent #1,268,909.

One type of trim tile formed or pressed in the press of the instant invention is indicated by the letter T and illustrated in Fig. 17. Obviously other forms or types of trim tile may be pressed by suitable changes in the die-heads.

Having described our invention, we claim:

1. In a mechanically-actuated press for trim tile, the combination with a die cavity, upper and lower plungers having cooperating tile-pressing die-heads, each provided with horizontal flat surfaces and rib-forming extensions projecting from said flat surfaces, mechanically-actuated means for moving said plungers and die heads into tile-pressing position below the level of the top of said die cavity, means for producing a separating tile-releasing movement of said plungers and die-heads from each other and causing a movement to an elevated position above the level of the top of the die cavity of said lower die-head and its projecting rib-forming extension, a mechanically-

actuated tile-ejecting and charging device synchronized with the movement to elevated position of the said lower die-head and having a portion movable over the surface of the die-head while in elevated position to push a trim tile off said lower die-head and across the die cavity into an initial position of said tile adjacent to the outer edge of said die cavity, and means for again moving said trim tile from said initial position to a position further removed from said die cavity.

2. In a mechanically-actuated press for trim tile, the combination with a die cavity, upper and lower plungers having cooperating tile-pressing die-heads, each provided with horizontal flat surfaces and rib-forming extensions projecting from said flat surfaces, mechanically-actuated means for moving said plungers and die-heads into tile-pressing position below the level of the top of said die cavity, means for producing a separating tile-releasing movement of said plungers and die-heads from each other and simultaneously causing a movement to an elevated position above the level of the top of the die cavity of said lower die-head and its projecting rib-forming extension, a mechanically-actuated tile-ejecting and charging device having an initial movement synchronized with the movement of the said lower die-head to said elevated position for pushing a trim tile in an initial ejecting movement over the surface of said lower die-head and across the die cavity while said lower die-head is in elevated position, and means for causing said tile-ejecting and charging device to have a secondary movement synchronized with the lowering movement of the die-head for moving the tile in a secondary movement out of the press when said lower die-head has been lowered below the level of the die cavity.

3. In a mechanically-actuated press for trim tile, the combination with a die cavity, upper and lower plungers having cooperating tile-pressing die-heads, each provided with horizontal flat surfaces and rib-forming extensions projecting from said flat surfaces, mechanically-actuated means for moving said plungers and die-heads into tile-pressing position below the level of the top of said die cavity, means for producing a separating tile-releasing movement of said plungers and die heads from each other and simultaneously causing a movement to an elevated position above the level of the top of the die cavity of said lower die-head and its projecting rib-forming extension, a mechanically-actuated tile-ejecting and charging device having an initial movement synchronized with the movement of the said lower die-head to said elevated position for pushing a trim tile in an initial ejecting movement over the surface of said lower die-head and across the die cavity while said lower die-head is in elevated position, and means for causing said tile-ejecting and charging device to have a secondary movement across the die cavity synchronized with the lowering movement of the said lower die-head, an off-bearing belt, a tile-transfer device movable from a position adjacent to the die cavity to a position adjacent to said off-bearing belt and adapted to receive and support a tile upon initial movement thereof from the lower die-head, and means connected with said tile-ejecting and charging device and operable during said secondary movement thereof to move said transfer device from a position adjacent to the die cavity to the off-bearing belt.

4. In a mechanically-actuated press for trim tile, the combination with a die cavity, upper

and lower plungers having cooperating tile-pressing die-heads, each provided with horizontal flat surfaces and rib-forming extensions projecting from said flat surfaces, mechanically-actuated means for moving said plungers and die-heads into tile-pressing position below the level of the top of said die cavity, means for producing a separating tile-releasing movement of said plungers and die heads from each other and simultaneously causing a movement to an elevated position of the lower die-head and its projecting rib-forming extension above the level of the top of the die cavity, a mechanically-actuated tile-ejecting and charging device having portions movable to opposite sides of the die cavity, a cam mechanism for actuating said tile-ejecting and charging device to have a double forward movement comprising an initial movement timed to move the tile over said lower die-head and across the die cavity while the lower die-head is raised to elevated position above the level of said cavity and a further secondary movement timed with the depression of the lower die-head to move across the die cavity and actuate said transfer mechanism, a tile-transfer device movable from a position adjacent to the die cavity to a second position further removed therefrom and adapted to receive and support a tile upon initial movement thereof from the die cavity, an off-bearing belt arranged adjacent to said second tile position, actuating means connected with said ejecting and charging device for moving said transfer device from its initial position adjacent to the die cavity to said position adjacent to said off-bearing belt and returning the same to said initial position.

5. In a mechanically-actuated press for trim tile, the combination with a die cavity, upper and lower plungers having cooperating tile-pressing die-heads, each provided with horizontal flat surfaces and rib-forming extensions projecting from said flat surfaces, mechanically-actuated means for moving said plungers and die-heads into tile-pressing position below the level of the top of said die cavity, means for producing a separating tile-releasing movement of said plungers and die heads from each other and simultaneously causing a movement to an elevated position above the level of the top of the die cavity of said lower die-head and its projecting rib-forming extension, a mechanically-actuated tile-ejecting and charging device having an initial movement synchronized with the movement of the said lower plunger to said elevated position for pushing a trim tile in an initial ejecting movement over the surface of said lower die-head and across the die cavity while said lower die-head is in elevated position, and means for causing said tile-ejecting and charging device to have a secondary forward movement across the die cavity synchronized with the lowering movement of the said lower die-head, an off-bearing belt, a tile-transfer device movable from a position adjacent to the die cavity to a position adjacent to said off-bearing belt and adapted to receive and support a tile upon initial movement thereof from the lower die-head, and means connected with said tile-ejecting and charging device and operable during said secondary movement thereof to move said transfer device from a position adjacent to the die cavity to the off-bearing belt, said tile-ejecting and charging device being provided with side rails reciprocable at opposite sides of the die cavity and having a latch adapted upon said secondary forward

11

movement to engage the tile-transfer device and to move the same from a position adjacent to the die cavity to said off-bearing belt and to release said transfer device in its return movement.

6. In a mechanically-actuated press for trim tile, the combination with a die cavity, upper and lower plungers having cooperating tile-pressing die-heads, each provided with horizontal flat surfaces and rib-forming extensions projecting from said flat surfaces, mechanically-actuated means for moving said plungers and die-heads into tile-pressing position below the level of the top of said die cavity, means for producing a separating tile-releasing movement of said plungers and die heads from each other and simultaneously causing a movement to an elevated position above the level of the top of the die cavity of said lower die-head and its projecting rib-forming extension, a mechanically-actuated tile-ejecting and charging device having an initial movement synchronized with the movement of the said lower die-head to said elevated position for pushing a trim tile in an initial ejecting movement over the surface of said lower die-head and across the die cavity while said lower die-head is in elevated position, and means for causing said tile-ejecting and charging device to have a secondary movement across the die cavity synchronized with the lowering movement of the said lower die-head, an off-bearing belt, a tile-transfer device movable from a position adjacent to the die cavity to a position adjacent to said off-bearing belt and adapted to receive and support a tile upon initial movement thereof from the lower die-head, said tile-ejecting and charging device being provided with side rails reciprocable at opposite sides of the die cavity and having a latch adapted upon said secondary forward movement to engage the tile-transfer device and to move the same from a position adjacent to the die cavity to said off-bearing belt and to release said transfer device in its return movement and said transfer mechanism comprising guide members having guide grooves, slides mounted to slide freely in said grooves and a grill comprising round anti-friction bars mounted on said slides to provide anti-friction elements in said transfer device.

7. In a mechanically-actuated press for trim tile, the combination with a die cavity, upper and lower plungers having cooperating tile-pressing die-heads, each provided with horizontal flat surfaces and rib-forming extensions projecting from said flat surfaces, mechanically-actuated means for moving said plungers and die-heads into tile-pressing position below the level of the top of said die cavity, means for producing a separating tile-releasing movement of said plungers and die heads from each other and simultaneously causing a movement to an elevated position of the lower die-head and its projecting rib-forming extension above the level of the top of the die cavity, a mechanically-actuated tile-ejecting and charging device having portions movable to opposite sides of the die cavity, a cam mechanism for actuating said tile-ejecting and charging device to have a double forward movement comprising an initial movement timed to move the tile over said lower die-head and across the die cavity while the lower die-head is raised to elevated position above the level of said cavity and a further secondary movement

12

timed with the depression of the lower die-head to move across the die cavity, a tile-transfer device adapted to receive and support a tile upon initial movement thereof from the die cavity and movable from a position adjacent to the die cavity to a tile-delivery position further removed therefrom, said ejecting and charging device having side rails movable along the bed of the press and having a latch adapted on said secondary forward movement to engage the transfer device and to move the same from said position adjacent to the die cavity to said tile-delivery position, an off-bearing belt arranged adjacent to said tile-delivery position, said transfer device comprising guide members having guide grooves, slides mounted to slide freely in said grooves and a grill comprising round anti-friction bars mounted on said slides to provide anti-friction elements in said transfer device.

8. In a mechanically-actuated press for trim tile, the combination with a die cavity, upper and lower plungers having cooperating tile-pressing die heads, each provided with horizontal flat surfaces and rib-forming extensions projecting from said flat surfaces, mechanically-actuated means for moving said plungers and die heads into tile-pressing position below the level of the top of said die cavity, means for producing a separating tile-releasing movement of said plungers and die heads from each other and causing a movement to an elevated position above the level of the top of the die cavity of said lower die-head and its projecting rib-forming extension, an off-bearing belt positioned at one edge of the press, a tile transfer device mounted on the press to reciprocate freely from an initial set position at the front edge of the die cavity to said off-bearing belt, means for moving a tile from said die-head to said transfer device, means for moving said transfer device with its loaded tile from the edge of the die cavity to said off-bearing belt to deliver said tile thereto, and means for moving said transfer device to said initial set position.

9. In a mechanically-actuated press for trim tile, the combination with a die cavity, upper and lower plungers having cooperating tile-pressing die heads, each provided with horizontal flat surfaces and rib-forming extensions projecting from said flat surfaces, mechanically-actuated means for moving said plungers and die heads into tile-pressing position below the level of the top of said die cavity, means for producing a separating tile-releasing movement of said plungers and die heads from each other and causing a movement to an elevated position above the level of the top of the die cavity of said lower die-head and its projecting rib-forming extension, an off-bearing belt positioned at one edge of the press, a reciprocable tile transfer device mounted on the press and comprising a grill composed of guide members provided with grooves, slides mounted in said grooves to reciprocate freely back and forth therein and a series of anti-friction round bars mounted at opposite ends on said slides, means for moving a tile from said die-head to said grill, means for moving said grill from the edge of the die cavity to said off-bearing belt to deliver said tile thereto, and means for moving said grill to said initial set position.
